Inventor

William E. Wall,

UNITED STATES PATENT OFFICE.

WILLIAM E. WALL, OF CHICAGO, ILLINOIS.

FOLDING LEVEL AND PLUMB.

1,249,698.

Specification of Letters Patent. Patented Dec. 11, 1917.

Application filed June 19, 1914, Serial No. 846,129. Renewed July 5, 1917. Serial No. 178,784.

To all whom it may concern:

Be it known that I, WILLIAM E. WALL, a citizen of the United States, residing at Chicago, in the county of Cook and State 5 of Illinois, have invented certain new and useful Improvements in Folding Levels and Plumbs, of which the following is a specification.

My invention relates to levels and plumbs 10 and more particularly to the type of folding levels and plumbs.

The primary object of my invention resides in the provision of a level and plumb that can be easily and quickly folded into 15 a compact form for facilitating the carrying of the same from place to place in a tool box.

Another object of my invention resides in the provision of a plurality of level sections 20 having novel means associated with the adjacent ends thereof for pivoting the sections together.

A further object of my invention resides in the provision of a novel means associated 25 with the connecting means of the sections for releasably holding the sections in a substantially rigid extended form, the locking means being easily and quickly disengaged when it is desired to fold the level.

A still further object of my invention resides in the provision of a device of the character described that is simple in construction, efficient in operation and one that can be manufactured and placed on the market at a minimum cost.

Other objects as well as the nature, characteristic features and scope of my invention will be more readily understood from the following description taken in connection with the accompanying drawings and 40 pointed out in the claims forming a part of this specification.

Referring to the drawings:

Figure 1 is a top plan view of my invention in an extended position;

Fig. 2 is a side elevational view of the same;

Fig. 3 is an enlarged side elevational view of my invention showing the sections folded;

Fig. 4 is an enlarged fragmentary elevational sectional view of the hinge members applied to the reduced ends of the adjacent sections; and

Fig. 5 is a perspective view of the hinge connection, the dotted lines showing the sections.

Referring more particularly to the drawings in which similar reference numerals designate like or corresponding parts throughout the different views, I provide a 60 level and plumb 1 which is composed of a plurality of sections 2 formed preferably of wood, having reduced ends 3 for the reception of the hinge members generally designated 4 and 5.

Each of the members 4 in this instance consists essentially of a substantially U-shaped plate, the arms 6 and 7 of which are arranged in parallel relation with each other and provided with uniformly spaced 70 openings 8 for the reception of suitable fastening devices for facilitating the securing of the same to the reduced ends 3 in order that the outer surfaces of the arms lie in alinement with the outer surfaces of the 75 sections 2. The vertex 9 of the member 4 has a plurality of uniformly spaced tubular ears 10 extending from one end thereof and the opposite end at the point of distortion of the arm 7 is depressed to provide a recess 11 for a purpose to be hereinafter 80 described.

The other of the hinge members 5 which in this instance consists essentially of a substantially U-shaped plate, comprising spaced 85 parallel arranged arms 12 and 13 having openings similar to the openings 8 in the other of the members for the reception of suitable fastening devices for facilitating the securing of the same to the reduced end 90 of the adjacent section in order that the outer surfaces of the arms will lie in alinement with the outer surfaces of the section. One end of the vertex 14 of the member 5 being provided with a plurality of uniformly spaced ears 15 which are arranged in alinement with the ears 10 and through which ears 10 and 15 is passed a pintle 16 for pivotally securing the members together, the other end of the vertex is provided at 100 its point of distortion with a transversely extending slot 17 and which slot communicates with a longitudinally extending slot 18, the latter being positioned intermediate the sides of the arm 13 of the hinge member 105 5 for a purpose to be hereinafter described. Ears 19 are provided on the side edges adjacent the point of distortion of the arm 13 and the vertex 14 of the member 5 and in which ears is rotatably mounted a pin 20, 110 the latter having rigidly connected thereto a pawl 21, the inner end of which is beveled

for engagement with the beveled portion 22 of the vertex 9 of the member 4 carried by the adjacent section for facilitating engagement with the recess 11 therein, the other 5 end of the pawl is reduced intermediate its ends to provide a handle portion 23 for reception at times within the inwardly extending and tapering recess 24 provided on the reduced ends 3 of the section at a point 10 in alinement with the slot 18 in the plate 13.

For the purpose of maintaining the pawl normally in alinement with the outer surface of the section and the outer surface of the arm 13, I have disposed about the pin 20 positioned within a recess in the reduced end a coil spring 25, the opposite ends of which are rigidly connected in any suitable manner to the pawl 21 and the pin 20.

For the purpose of protecting the free reduced ends of the outer sections, I have rigidly connected to the same by means of suitable fastening devices substantially U-shaped plates 26.

Each of the sections 2 are provided intermediate their ends with openings 27 in which are suitably and rigidly mounted level tubes 28, the latter being further held in position by means of the retaining rings 29 embedded about the openings on the opposite sides of 30 the sections and secured thereto by means of suitable fastening devices. In order to facilitate matters when leveling, the tubes in some of the sections are disposed longitudinally of the sections while in the remaining 35 sections they are disposed transversely of the sections as clearly shown in Fig. 1 of the drawings.

The operation of my invention is as follows:

Assuming that the level is in an extended position as shown in Fig. 1, all that is necessary to do is for the user to place one of his fingers (not shown) upon the handle portion 23 of the pawl 21 and press the same 40 into the recess 24 which causes the inner end of the pawl to be disengaged from the recess 11 on the other of the hinge members. The sections are now bent upon themselves and the operation is repeated at the end of each 45 section until the same has been completely collapsed and placed in a compact form. When it is desired to extend the level, all that is necessary to do is for the user to grasp two of the adjacent sections with his 50 hands (not shown) and press the same into alinement with each other which causes the beveled face of the pawl to bear against the beveled portion 22 of the adjacent member and facilitating the automatic locking 55 engagement of the inner end of the pawl with the recess. The spring 25 which at all times holds the pawl 21 in alinement with the outer surface of the arm 13 in the section to 60 which it is connected assures the locking of 65 the members.

Although I have shown and described the preferred embodiment of my invention, I desire it to be understood that I am not limited to the exact details shown, however, I desire that great stress be laid upon the construction and arrangement of the hinge members which have the locking means associated therewith for securing the sections in a rigid set-up position.

From the above description taken in connection with the accompanying drawings, it can be easily seen that I have provided a device that is simple in construction containing but a few simple parts that can be cheaply manufactured and assembled and when assembled can be placed upon the market and sold at a minimum cost.

It will be understood that the above description and accompanying drawings comprehend only the general and preferred embodiment of my invention and that various minor changes in detail of construction, proportion and arrangement of the parts may be made within the scope of the appended claims and without sacrificing any of the advantages of my invention.

Having thus fully described my invention, what I claim as new and desire to secure by Letters Patent, is:—

1. A folding level and plumb including a plurality of pivotally connected sections, and independently automatically operable latch means pivotally associated with the adjacent ends of the sections for removably holding the sections in an extended form.

2. A folding level and plumb including a plurality of pivotally connected sections, and a resiliently controlled latch pivotally mounted and embedded in the end of one of said sections and associated with the adjacent section for holding said sections in an extended form.

3. A folding level and plumb including a plurality of sections, means for pivoting the sections together, and independent resiliently controlled locking means pivotally associated with the pivoting means of the sections and arranged flush with the sections for detachably holding the sections in an extended form.

4. A folding level and plumb including a plurality of sections having reduced ends, substantially U-shaped plates secured to the reduced ends of the adjacent sections, means for pivoting said plates together, resiliently controlled locking means associated with the plates for releasably holding the sections in an extended form, said locking means being arranged flush with the upper surfaces of the sections.

5. A folding level and plumb including a plurality of sections having reduced ends, a substantially U-shaped plate secured to the reduced end of each section, means for pivoting said plates together, and a resiliently

controlled locking means movably mounted in one of said plates and associated with the other of the plates for holding the sections in an extended form.

6. A folding level and plumb including a plurality of sections having reduced ends, substantially U-shaped plates carried by the reduced ends of the adjacent sections, means for pivotally connecting said plates, and a resiliently controlled pawl pivotally mounted in one of said sections for detachable engagement with the plate on the adjacent section for holding said sections in an extended form, said pawl being arranged flush with the upper surfaces of the sections.

7. A folding level and plumb including a plurality of sections, substantially U-shaped plates carried by the ends of the adjacent sections, means for pivotally connecting said plates, one of said plates provided with a recess, and a pawl pivotally mounted on the other of said plates and engageable in said recess for removably holding the sections in an extended form.

8. A folding level and plumb including a plurality of sections, substantially U-shaped plates carried by the ends of the adjacent sections, means for pivotally connecting said plates, one of said plates provided with a

recess, a pawl pivotally mounted on the other of said plates and engageable in said recess for removably holding the sections in an extended form, and means for preventing the accidental displacement of the pawl from the recess.

35

9. A folding level and plumb including a plurality of sections having reduced ends, substantially U-shaped plates carried by the reduced ends of the adjacent sections, a plurality of uniformly spaced ears extending from said plates, means engaging said ears for pivotally connecting said plates, one of said plates provided with a transverse recess, a pawl pivotally mounted on the other of said plates and engageable in the recess for removably holding the sections in an extended form, and resilient means associated with the pawl for preventing accidental displacement of the pawl from the recess and holding the pawl in alignment with the plates.
